CLAIM

I claim the ornamental design for an explosion proof camera, as shown and described.

DESCRIPTION

FIG. 1 is a top, front and right side perspective view of an explosion proof camera showing the claimed design;
FIG. 2 is a front elevation view thereof;
FIG. 3 is a back elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The broken lines depict portions of an explosion proof camera in which the design is embodied that form no part of the claimed design.
